Primary Examiner—Alan P. Douglas**Assistant Examiner—Antoine D. Davis****Attorney, Agent, or Firm—Terry M. Gernstein****[57] CLAIM**

The ornamental design for a building material cutting guide, as shown and described.

DESCRIPTION

FIG. 1 is a perspective view of the building material cutting guide embodying the design of the present invention;

FIG. 2 is a front elevational view thereof;

FIG. 3 is a rear elevational view thereof;

FIG. 4 is an end elevational view thereof;

FIG. 5 is an end elevational view thereof;

FIG. 6 is a top plan view; and,

FIG. 7 is a bottom plan view thereof.

FIG. 1

FIG. 2

FIG. 3

FIG. 4

FIG. 5

FIG. 6

FIG. 7
